BY Mann L.
ATTORNEYS.

UNITED STATES PATENT OFFICE.

WRIGHT W. HALL, OF NEW WINDSOR, COLORADO.

DESIGN FOR A FRAME FOR BRIDLE-BITS.

SPECIFICATION forming part of Design No. 21,872, dated September 27, 1892.

Application filed April 9, 1890. Serial No. 347,274. Term of patent 7 years.

To all whom it may concern:

Be it known that I, WRIGHT W. HALL, a citizen of the United States, residing at New Windsor, in the county of Weld and State of Colorado, have invented and produced a new and original Design for a Frame for a Bridle-Bit, of which the following is a description, reference being had to accompanying drawing, which exhibits a perspective view of the said frame.

The letters A A indicate two oblong and slightly-curved side plates arranged opposite each other, and B a cross-bar arranged at about the middle of their length. There is a

series of holes in plates A A around the ends 15 of the said bar B. Between the lower portions of the side plates A A is arranged the curved round bar C, that projects forward. The lower ends of the plates A are provided with curved slots. 20

What I claim is—

The design for the frame of a bridle-bit, as shown and described.

WRIGHT W. HALL.
